C. E. BATEMAN

WINDOW

Filed Oct. 5, 1926

UNITED STATES PATENT OFFICE.

CHARLES E. BATEMAN, OF MINNEAPOLIS, MINNESOTA.

WINDOW.

Application filed October 5, 1926. Serial No. 139,630.

My invention relates to windows and particularly to the type of window known as the double-hung window, and has for its object to provide a construction whereby two sashes are supported for vertical sliding movement in offset relation so that either of the sashes may be independently moved from one position within the frame to another.

Another object of the invention resides in forming the frame of the window with a column disposed between the two sashes, and in further providing said sashes with sliding friction strips adapted to co-act with said column.

A still further object of the invention resides in providing guide strips adapted to be attached to said column for bringing said sliding friction strips into frictional engagement with said column so as to hold said sashes in any of the positions of adjustment thereof.

A still further object of the invention resides in providing said guide strips with projections thereon adapted to overreach the corners of the sashes.

A still further object resides in providing a window construction of the double-hung type in which the usual sash cords, weights and pulleys may be completely dispensed with so that a plank frame may be utilized in place of the usual box frame.

With the foregoing and other objects in view, which will appear in the following description, the invention resides in the novel combination and arrangement of parts and the details of construction hereinafter described and claimed.

In the drawings:

Fig. 1 is a perspective view of a window illustrating an embodiment of my invention.

Fig. 2 is a fragmentary plan sectional view of a portion of the window illustrated in Fig. 1 drawn to an enlarged scale.

In the ordinary double-hung window considerable inconvenience and annoyance is encountered when the window sashes and frame swell or shrink under varying atmospheric conditions, causing the window either to stick and prevent the ready raising of the sashes or causing the sashes to fit so loosely

in the frame as to produce rattling. My invention overcomes these objections by providing a construction whereby the sashes are properly held in frictional sliding relation along the frame, which structure permits of adjustment to compensate for shrinkage or swelling occurring in the continued use of the sashes.

The window proper as best shown in Fig. 1, comprises a frame A in which is slidably mounted two sashes B and C. The frame A consists of uprights 10 fitted with a suitable header (not shown) and with a sill 11. This frame may be further constructed with an interior casing 12 and an exterior casing 13 for giving the frame the desired ornamental appearance, as well as a stool 14 and an apron 15, all of usual construction. The uprights 10 are constructed in the usual manner except that the stops and parting strips customarily used in conjunction with the same are in my invention completely omitted. Instead of this construction, I form a groove 16 along each of the uprights 10 in which is positioned a vertical column 17 extending inwardly into the opening of the frame for a purpose to be presently described. The frame is constructed of such dimensions that the sashes when installed 70 may butt against the edge 18 of said column 17 to close the opening through the frame proper.

Both of the sashes B and C are similar to the sashes now in common use and may be constructed without check rail, if desired, as shown in the drawings. These sashes comprise stiles 19 and 20 connected together by rails 21 and 22, which stiles and rails are rabbeted to receive window 90 panes 23 in the usual manner. Along the edges of the stiles 19 and 20 of the two sashes B and C are grooves 24 which snugly receive sheet metal sliding friction strips 25, said strips being held in place within 95 said grooves by means of nails 26 passing through said stiles and through said strips. These sliding friction strips extend outwardly beyond the sashes proper and engage the column at the sides 27 and 28 thereof. In conjunction with this construction, I employ two guide strips 29 and 30

which fit between the edges of the sashes B and C and the uprights 10 of frame A. These guide strips are adapted to contact with the sliding friction strips 25 and are held in frictional engagement therewith through the agency of a number of wood screws 31 which pass through the guide strips 29 and 30 and are screwed into the columns 17. These guide strips are recessed 10 as indicated at 32 forming shoulders on each side thereof abutting against the surfaces 27 and 28 of column 17 on one side and on the sliding friction strips 25 on the other side. With this construction the pressure 15 against the sliding friction strips 25 and consequently the friction tending to hold the sashes in adjusted positions may be readily varied by turning the screws 31.

For the purpose of finishing off the window and giving the same an attractive appearance the guide strips 29 and 30 are caused to extend outwardly beyond the sashes proper and are formed with projections 32 adapted to overlie the edges of said 25 sashes, and weather guard the joints between the sashes and said strips 29 and 30. The frame A is constructed of a size so that the sashes B and C fit loosely along the column 17 and the guide strips 29 and 30, projections 32 being sufficiently spaced from the sashes to permit of the proper adjustment of said guide strips to cause the desired frictional tension for holding the sashes in adjusted positions. 35 By adjusting the screws 31 and thereby appropriately frictionally binding the sliding friction strips 25 between the columns 17 and the guide strips 29 and 30, though readily shiftable, the window sashes are 40 maintained in any desired position. Due to the accurate adjustment possible through the screws 31 it can readily be conceived that the sashes may be so hung that the same may be raised and lowered at will and so that 45 said sashes remain in such raised and lowered positions without further attention.

Although I have illustrated the window sashes constructed of wood, yet it can readily be comprehended that the same may be 50 constructed of sheet metal or of any other desired material. In the drawings the sliding friction strips have been illustrated as constructed of a single sheet of material. It will, however, become apparent that other 55 construction may be utilized in place thereof, having a yielding frictional engagement with the column and guide strips so that further adjustment of the said guide strips becomes unnecessary after the window has been first installed.

With my invention window weights, cords and pulleys are entirely dispensed with and the frame proper may be constructed at 60 smaller cost than the usual box frame now customarily employed with double-hung 65

windows for the encasing of the window weights used in conjunction therewith. Swelling or shrinkage of the sashes proper due to changes in relative humidity or temperature of the atmosphere will not affect 70 the mounting of the sashes due to the fact that the same are primarily supported through the sliding friction strips attached thereto. Swelling or shrinkage of the structure along which said sliding friction 75 strips move can be readily compensated for by adjusting the guide strips. With my invention a perfectly tight window closure is provided accomplishing the results obtained in the ordinary window with the use of 80 weather strips or other additional sealing means.

Changes in the specific form of my invention, as herein disclosed, may be made within the scope of what is claimed without departing from the spirit of my invention. 85

Having described my invention what I claim as new and desire to protect by Letters Patent is:

1. A window comprising a frame, a column positioned along said frame, a pair of sashes slidably mounted within said frame having the edges of the stiles thereof abutting against said column, one stile over-reaching said column at one side thereof and the other stile over-reaching the column at its other side, sliding friction strips attached to said sashes and adapted to co-act with said column, and guide strips attached to the sides of said column for bringing said sliding friction strips in frictional engagement therewith. 90

2. A window comprising a frame, a column positioned along said frame, a pair of sashes slidably mounted within said frame having the edges of the stiles thereof abutting against said column, a sliding friction strip on one sash for engagement with one side of said column, a sliding friction strip on the other sash for engagement with the other side of the column, and guide strips attached to said sides of said column for bringing said sliding friction strips into frictional engagement therewith, said guide strips being formed with projections overlying said sashes. 105

3. A window comprising a frame, an inwardly projecting column positioned along said frame, a sash slidably mounted within said frame and along said column, a friction strip attached to said sash and extending partially across a side of said column and lying in contact therewith, a guide strip positioned along the side of said column, said guide strip being formed with a longitudinal groove, the portion of said guide strip on one side of said groove contacting with said column and the portion on the other side of said groove contacting with 110 said sealing strip and fastening means ex- 115

tending through said groove for securing said guide strip to said column.

4. In a window, a frame, a column positioned along said frame, a sash slidably mounted in said frame, a sliding friction strip issuing from said sash and adapted to co-act with said column, and a tension-
- 5

ing guide strip adjustably supported adjacent to said column for bringing said sliding friction strip into frictional engagement with the column. 10

In testimony whereof, I have signed my name to this specification.

CHARLES E. BATEMAN.
